(57) **CLAIM**

The ornamental design for an watermelon float, as shown
and described.

DESCRIPTION

FIG. 1 is a perspective view of a watermelon float in
accordance with the invention.

FIG. 2 is a top view of the watermelon float in accordance
with the invention.

FIG. 3 is a bottom view of the watermelon float in accordance
with the invention.

FIG. 4 is a first side view of the watermelon float in accordance
with the invention.

FIG. 5 is a second side view of the watermelon float in accordance
with the invention, wherein the second side is
opposite the first side.

FIG. 6 is a front view of the watermelon float in accordance
with the invention; and,

FIG. 7 is a rear view of the watermelon float in accordance
with the invention.

The larger type broken lines shown in FIGS. 1-7 are of
various surface features of the watermelon float that form no
part of the claimed design. The smaller type broken lines
shown in FIGS. 1-7 represent stitching and are part of the
claimed design.

1 Claim, 6 Drawing Sheets
